HEATER

Filed July 25, 1917

Inventor:
John W. Neumann,
By George A. Remington
his Atty.

UNITED STATES PATENT OFFICE.

JOHN W. NEUMANN, OF ST. LOUIS, MISSOURI.

HEATER.

Application filed July 25, 1917. Serial No. 182,601.

To all whom it may concern:

Be it known that I, JOHN W. NEUMANN, a citizen of the United States, and resident of St. Louis, in the State of Missouri, have 5 invented certain new and useful Improvements in Heaters, of which the following is a specification.

This invention relates to heating devices and more particularly to a unitary radiator 10 structure for heating rooms with gas burners or other heating elements. It has for its principal objects to eliminate the resultant excess moisture and more particularly the noxious fumes and the dampness usually 15 resulting from burning gas; to minimize fuel consumption and secure the maximum benefit of the heat of combustion; and to attain certain other advantages as will hereinafter more fully appear.

20 The invention consists in the novel apparatus and in the combinations and arrangements of parts hereinafter described and claimed.

In the accompanying drawing forming 25 part of this specification and wherein like characters refer to like parts wherever they occur,—

Figure 1 is a side elevation of a radiator constructed and arranged according to the 30 invention;

Figure 2 is a longitudinal, vertical section;

Figure 3 is a horizontal section taken on or about the line 3—3' of Figure 1;

Figure 4 is a fragmentary, transverse, 35 vertical section on the line 4—4' of Figure 1; and

Figure 5 is a top plan view of the burner detached.

Referring now to the drawing, the numerals 1, 2, indicate the side walls, and 3, 4 indicate the end walls of a rectangular, hollow shell, the joints at the corners of which are hermetically sealed. As shown, the corner joints are effected by flanging the 40 meeting edges of the walls which are of relatively thin sheet metal, and inserting said flanged portions into slotted tubes 5, which tubes are filled with a suitable cement after the flanges have been spread back 45 against the inner faces of the tubes (see Figure 3). The tubes 5 extend below the

bottom of the shell to provide legs for supporting it above the floor.

The top plate 6 of the shell is also hermetically sealed at its edges which are joined 55 with the side and end walls. This is accomplished as shown in Figures 2 and 4, as by flanging the edge portions of the top plate upward and rebending the upper edge portions of the side and end walls inward 60 and downward to receive said upstanding flanges of the top plate, and then riveting or bolting the engaged marginal portions together. On the top plate is secured, as by rivets or bolts, a shorter and narrower supplemental plate 7 whose marginal portions are flanged upward; and between said flanges and the engaged marginal portions of the top plate 6 and the side and end walls is a filling of cement. 70

Approximately one-half of the bottom of the shell is open, and the bottom plate 8 is secured at its edges to the side and end walls in a manner similar to the top plate 6. One end portion of this bottom plate is 75 turned upward, as at 9, to constitute a division wall or baffle, and its side marginal portions are flanged, as at 10, and riveted or otherwise secured tight against the side walls 1 and 2 of the shell. The upper edge 80 portion 11 is turned at an inclination toward the end wall 4, and just below this inclined portion is a horizontal slot or a series of perforations 12, the purpose of which will be later explained. 85

Extending into the shell, through the end wall 3, centrally between the side walls 1 and 2, and in a plane a little higher than the bottom plate 8, is a gas burner 13, which is designed to produce a long, narrow, 90 blade-like or flat wick flame. The preferred arrangement of the jet orifices of the burner for accomplishing this is best shown in Figure 5, there being two double parallel rows in staggered relation, as indicated by 95 the numeral 14. Aside from this feature the burner construction, of itself, forms no particular part of the present invention, but will be subject matter of a separate application I am about to make. 100

The burner extends with its inner end close to the upturned portion 9 of the bot-

tom plate 8, and it is supported near its ends by cross pieces 15, 16, which are fastened at their ends to the side walls 1 and 2 of the shell. The burner is fastened to the cross piece 15 by a yoke or strap 17 whose end portions extend upward through perforations in the cross piece and are screw-threaded to receive securing nuts 18. At its opposite end the burner is fastened to the cross piece 16 by a screw or bolt 19.

Secured to the under side of the burner and spaced therefrom, as by blocks or sleeves 20 through which screws 21 are passed, is a guard and baffle plate 22, which extends substantially the entire length of the bottom opening of the shell, but is considerably narrower, so as to provide elongated openings 23 on opposite sides of the burner. The side walls 1 and 2 and the end wall 3 are provided with a multiplicity of perforations 24 in the zone of combustion; and the end wall 3 has an opening 25 provided with a door 26 for convenience in lighting the burner.

Located centrally in the shell, between the side walls 1 and 2, and extending diagonally from the upper corner of the end wall 3 and top plate 6 to the lower corner of the end wall 4 and bottom plate 8, is a pipe 27 whose lower end is open. Its upper end is connected to a transverse, horizontal coupling pipe section 28 which extends through the side wall 2 of the shell and is securely fastened by collars 29 and 30 thereon which clamp said wall 2.

On the outside of the shell the coupling pipe section 28 has a pipe 31 connected thereto and extending substantially parallel with the pipe 27. At its lower end this pipe 31 is connected to a short pipe section 32 which is open at its end and extends through the wall 2 into the shell close to the bottom at the lower corner of the end wall 4 and is secured to said wall 2 in the same manner as the above mentioned pipe section 28.

Extending parallel with and under the pipe 31 is a pipe 33 whose upper end portion is provided with a cap 34 having a vent opening 35 therein (see Figure 3), and whose lower end is open and projects into the neck 36 of a receptacle 37, said neck being of slightly larger diameter than the pipe so as to provide clearance for an air inlet opening around the pipe, as will be later explained. About midway between their ends the pipes 31 and 33 are connected by a cross pipe 38. As shown, this connection is effected by an H-shape coupling to which the pipes, which are respectively in two sections, are attached. In this way the pipe 31 which is secured to the wall 2 supports the pipe 33.

The action of the apparatus will now be described: The burner being lighted, the air to support combustion is drawn in

through the openings 23 at the bottom and also through the perforations 24 in the side walls.

Obviously, the greatest heat is in the zone directly above the burner and the lowest temperature is at the lower corner of the shell adjacent to the bottom plate 8 and end wall 4. Owing to the arrangement of the partition wall 9 having the lip 11 and the horizontal slot or series of perforations 12, as the case may be, a rotary circulation is set up within the shell as indicated by the arrows in Figure 2. That is, the direction is upward above the flame, thence over the partition wall 9 towards the end wall 4 and downward and towards the partition wall 9, and thence through the opening 12 in said partition wall 9, the lip 11 serving as a baffle and axis, as it were, about which the current rotates. In the immediate region of the corner of the end wall 4 and bottom plate 8 where the pipe 27 terminates there is practically a dead space where there is no circulation.

Owing to this circulation, as above set forth, the heavier vapors and moisture resulting from the burning gas, particularly water gas, is thrown towards the end wall 4 and downward onto the bottom plate 8, and unless some means were provided to eliminate this moisture from the shell there would be an accumulation therein to such an extent as to cause imperfect combustion and produce noxious vapors and moisture which would be thrown out into the atmosphere in the room, the disadvantages and dangers of which are well known.

The elimination of the undesirable products of combustion is effected in the following manner: The upper portion of the pipe 27 being in the zone of greatest heat becomes heated to a high temperature. This causes a forced circulation up through the pipe 27, outward through the pipe 28, downward through the pipe 31 to the cross pipe 38, and thence upward through the pipe 33 and out through the vent opening 35. Hence, the heavier vapors thrown off by the before mentioned circulation within the shell are drawn into the pipe 27 and they are condensed in the pipes 31 and 33, the condensation being superinduced in the pipe 33 by the outside air which is drawn into the lower end of the pipe through the mouth of the receptacle 37, the water of condensation draining into the receptacle. In this way perfect combustion continues throughout the operation of the heater, the moisture is drawn out of the shell and collected in the receptacle, and the maximum benefit of the heat is obtained as it is given off from the walls of the shell by radiation, and by the elimination of noxious fumes and avoidance of an undue increase in humidity the disadvantages and danger ordinarily incidental

to the use of gas for heating rooms are overcome.

If desired the vent opening 35 may communicate with a suitable flue or direct to the atmosphere outside of the room, and the lower end of the pipe 33 may also lead to a suitable drain outside of the room, but it has been found that the device constructed and arranged as shown in the drawing can 10 be operated in a room without throwing off any unpleasant or noxious fumes or increasing the normal humidity in the room.

In order to provide a vent to let out gas should there be an undue accumulation 15 thereof in the shell before the burner is lighted, the top plate is provided with an opening 41 which is normally closed by a removable plug 42. There is also a similar opening 43 in the bottom plate. The bottom 20 plate also has thereon a layer of cement or other suitable non-conducting material as an insulation to protect the floor from the heat.

Obviously, other heating elements may be used instead of gas burners, the shell may 25 be made of cast metal instead of the sheet metal construction shown in the drawing, and the apparatus admits of considerable other modification throughout its entirety without departing from the spirit of the invention as defined in the appended claims, 30 and, therefore, is not limited to the exact construction and arrangement shown.

What is claimed is:

1. In a gas heat radiator, a hollow shell 35 having a gas burner therein, an exhaust duct in said shell, said duct having its intake end in the zone of lowest temperature and extending through the zone of highest temperature, and a condenser outside of said 40 shell and connected to the outlet end of said exhaust duct, said condenser having a vent opening and an air inlet, the vent opening being uppermost.

2. In a gas heat radiator, a hollow shell 45 having a gas burner therein and means for supporting combustion and setting up a rotative circulation of the products of combustion, an exhaust duct located in said shell with its intake end in the lowermost and 50 endmost part of the shell remote from the zone of combustion and extending upward with its upper portion in the zone of greatest heat, and a self-draining condenser located on the outside of the shell and connected to 55 the upper end of said exhaust duct, said condenser having a vent opening and an air intake, the vent opening being uppermost.

3. In a gas heat radiator, a hollow shell 60 having a gas burner therein, said shell having an air inlet only to the zone of combustion and being otherwise air-tight to confine the products of combustion, an exhaust duct in said shell with its intake end remote from 65 the zone of combustion and extending

through the zone of greatest heat, and a condenser on the outside of the shell and connected to the outlet end of said exhaust duct, said condenser having a vent opening and an air intake. 70

4. In a gas heat radiator, a rectangular, hollow shell, a gas burner located in the lower portion and near one end of said shell, said shell having air inlet openings in the region of said burner, but being otherwise 75 closed so as to confine the products of combustion, there being a partition wall dividing the lower part of said shell, an inclined pipe extending from the upper corner of the shell above the burner to the opposite lower corner of the shell, the lower end of the pipe being open and its upper end having a transverse extension projected through the side wall of the shell and connected to the upper end of a pipe located on the outside of the 80 shell and extending downward at an inclination and having a lateral extension at its lower end which is projected into the lower corner of the shell, a second pipe on the outside of the shell extending substantially 85 parallel with said other outer pipe and being cross connected thereto intermediate the ends thereof, said second mentioned outer pipe having a vented closure at its upper end and its lower end being open and projecting 90 into a receptacle with an open space between. 95

5. In a gas heat radiator, a rectangular, hollow shell, a gas burner located in the lower portion and near one end of said shell, said shell having air inlet openings in the region of said burner, but being otherwise 100 closed so as to confine the products of combustion, there being a transverse partition wall dividing the lower part of said shell, said wall extending to about the middle of 105 the shell and having its upper marginal portion turned towards the end of the shell opposite to that which the burner is adjacent, and being provided with an opening or openings just below said marginal portion, an inclined pipe extending from the upper corner of the shell above the burner to the opposite lower corner, the lower end of the pipe being open and its upper end having a transverse extension projected through the 110 side wall of the shell and connected to the upper end of a pipe located on the outside of the shell and extending downward at an inclination and having a lateral extension at its lower end which is projected into the lower corner of said shell, a second pipe on the outside of the shell extending substantially 115 parallel with said other outer pipe and being cross connected thereto intermediate the ends thereof, said second mentioned outer pipe having a vented closure at its upper end and its lower end being open and projecting into a receptacle with an open space between. 120

6. In a heater, a hollow shell, a heating 125

130

element therein, means for causing a revolving circulation of the body of products in said shell resulting from the action of said heating element, and a restricted exhaust tube located in said shell with its intake end in the zone of least heat and terminating close to the inner face of the bottom of the shell and in the peripheral region of the

revolving body of products, said tube extending upward through the zone of greatest 10 heat and leading outside the upper part of said shell.

Signed at St. Louis, in the State of Missouri, this 21st day of July A. D. 1917.

JOHN W. NEUMANN.
